UNITED STATES PATENT OFFICE.

JOHANN GODFREY PETERSON, OF BRIDGEPORT, CONNECTICUT, ASSIGNOR
TO THE BRYANT ELECTRIC COMPANY, OF BRIDGEPORT, CONNECTICUT,
A CORPORATION OF CONNECTICUT.

INCANDESCENT-LAMP SOCKET.

No. 844,829.

Specification of Letters Patent.

Patented Feb. 19, 1907.

Application filed July 5, 1906. Serial No. 324,918.

To all whom it may concern:

Be it known that I, JOHANN GODFREY PETERSON, a citizen of the United States of America, residing in the city of Bridgeport, in the county of Fairfield and State of Connecticut, have invented certain new and useful Improvements in Incandescent-Lamp Sockets, of which the following is a specification.

10 My invention relates to incandescent-lamp sockets and the like, and particularly to the means of fastening together the shell and the cap, the object of my invention being to provide a ready and secure means where-
15 by the parts may be attached or loosened.

In the accompanying drawings, Figures 1 and 2 represent side views of the opposite faces, respectively, of the cap and shell separated. Figs. 3 and 6 are perspective views 20 of the cap and shell, respectively. Figs. 4 and 5 are views of half-sockets, partly in section, taken respectively on the lines 4 4 and 5 5 in Fig. 7; and Fig. 7 is an enlarged cross-section on the line 7 7, Figs. 4 and 5. Fig. 8 25 is an enlarged perspective view of the upper portion of the shell; and Fig. 9 is an enlarged vertical elevation of the same, broken on the line 9 9, Fig. 8.

Referring to the drawings, the cap A and the 30 shell B are made of any suitable metal, preferably the usual drawn sheet metal. On the inner face of the rim C of the cap are provided two angled projections 1, facing in the same direction, preferably on opposite sides of the 35 rim, and each having one face *a* practically parallel to the axis of the socket and one face in a plane practically at right angles to the axis of the socket. At corresponding points 40 on the shell when the cap is fitted thereon are cut holes 2 to receive these projections. In the rim of the cap is cut also a hole 3 or, preferably, two such holes on opposite sides of the rim. A spring-tongue 4, having a pro-
jection 5, one face of which is beveled to act

as a catch, is provided on the shell at such a 45 point that the projection enters the hole 3 or one of the holes 3 in the cap when the cap is fitted on the shell and the projections 1 on the cap have entered the holes 2 in the shell.

On the projection 5 is provided a groove 6 50 or other convenient means to afford a seat for the finger-nail—for example, when pressing down the tongue 4 in order to free the projection 5 from the hole 3. The beveled face of this catch 5 opposes the face of the 55 angled projections 1.

Rotation of the cap in either direction is prevented, since the sides *a* of the projection 1 and the beveled face of the projection 5 meet the sides of the holes 2 and 3, respectively, when an attempt is made to revolve the cap on the shell.

Under normal conditions when the shell and cap are in position the sides *b* of the angled projections 1 prevent the shell from being withdrawn from the cap; but if the catch 5 be pushed down by means of the finger or finger-nail or otherwise and be thus freed of the hole 3 the shell may then be turned to free the holes 2 from the angled projections 1 and 70 the cap then removed.

I claim as my invention—

An incandescent-lamp socket having a cap and a shell, and means for fastening the same together, said means consisting of an angled 75 projection on the inner face of the cap-rim with a corresponding hole in the shell, a spring-tongue cut from the shell and bearing a beveled catch, the face of which opposes the face of the angled projection, and received by a corresponding hole in the cap.

In testimony whereof I have signed my name to this specification in the presence of two subscribing witnesses.

JOHANN GODFREY PETERSON.
